UNITED STATES PATENT OFFICE.

FINIS EWING ROACH, OF CHICAGO, ILLINOIS.

LAWN-SPRINKLER.

1,308,371.

Specification of Letters Patent. Patented July 1, 1919.

Application filed October 16, 1916. Serial No. 125,358.

To all whom it may concern:

Be it known that I, FINIS EWING ROACH, a citizen of the United States, and a resident of Chicago, in the county of Cook and State 5 of Illinois, have invented certain new and useful Improvements in Lawn-Sprinklers; and I do hereby declare that the following is a full, clear, and exact description thereof, reference being had to the accompanying 10 drawings, and to the letters of reference marked thereon, which form a part of this specification.

This invention relates to improvements in lawn sprinklers for use in watering lawns, 15 golf links, cricket pitches, gardens and the like. One of the objects of the invention is to provide an automatic cut-off for a revolving sprinkler nozzle. Another object of the invention is to provide means for regulating 20 the revolution or swing of the nozzle, whereby an even distribution of the volume of water over a prescribed area of the lawn or other surface desired to be irrigated by the sprinkler will take place. Another object 25 of the invention is to provide means for regulating the time of flow of the water through the sprinkler.

The sprinkler is so constructed that when 30 placed in operative position on a lawn, so that the water will sprinkle at one edge of the part to be irrigated, the sprinkler will gradually rotate over the desired area and will then be shut off when the water has reached the other limit of the said area. It 35 may be made to rotate in one complete circle and then stop, or it may be made to rotate over a space equal to a segment of the circle. This automatic control is an important feature of the invention.

40 In carrying out my invention, I provide a tubular casing in which is located a piston head, said piston head dividing the casing into two chambers. Said piston head has a stem in one of said chambers and upon this 45 stem is a rack bar, which is operatively connected to that end of an upright sprinkler nozzle located in said chamber. As the piston moves forwardly under the action of the pressure in said pressure chamber, a rotative movement is thus imparted to said nozzle. Means are provided for attaching a hose to 50 said casing to deliver water under pressure into said chamber, the water pressure acting to impart movement to said piston and rack bar, while the surplus of water issuing from 55 the sprinkler nozzle as it is rotating acts as

a spray curtain upon the prescribed area of lawn.

The other chamber is adapted to contain a resistance fluid, preferably water and as the 60 piston compresses the fluid therein, the fluid will escape very slowly from this second chamber and thus allow the piston to advance. An adjustable valve mechanism controls the escape of fluid from this second 65 chamber, so that the period of time of rotation of the nozzle may be governed.

The sprinkler is so constructed that when the sprinkler nozzle has rotated through a predetermined angle of rotation, the escape 70 of the water into and through the nozzle will be automatically shut off.

These objects, together with the several advantages of my improved lawn sprinkler, will appear as I proceed with my specification.

In the drawings:

Figure 1 is a perspective view, illustrating my improved lawn sprinkler attached to the end of a hose and in operation upon a 80 lawn.

Fig. 2 is a central, longitudinal, vertical sectional view on an enlarged scale.

Fig. 3 is a transverse, vertical, sectional view, taken upon the line 3—3 of Fig. 2, 85 looking in the direction indicated by the arrows.

Fig. 4 is a central, longitudinal, horizontal, sectional view, taken upon the line 4—4 of Fig. 2, looking in the direction indicated by the arrows.

Fig. 5 is a transverse, vertical, sectional view, taken upon the line 5—5 of Fig. 2, looking in the direction indicated by the 95 arrows.

Fig. 6 is a perspective view of the sprinkler nozzle.

Fig. 7 is a detail, sectional view on an enlarged scale, of the valve mechanism controlling the escape of resistance fluid as will 100 appear later.

Fig. 8 illustrates a modified form of sprinkler nozzle.

Referring now in detail to that embodiment of my invention illustrated in the accompanying drawings, 10 indicates as a whole my improved lawn sprinkler. It comprises a horizontally disposed tubular casing 11 which is attached to a suitable base 12 by means of a U shaped clamp 13. As 110 shown, said base has a semi-cylindric seat formed in a saddle 14, adapted to receive the

casing 11. The clamp 13 is arranged about the top of said casing in the plane of said saddle, screws 15, 15 attaching said clamp to said base in clamping engagement with 5 said tubular casing.

Removably attached to and closing one end of said casing (the left hand end as viewed in the drawings) is a cap 16. A gasket 17 is interposed between the upright 10 wall of the cap and the associated end of said tubular casing. Threaded upon the opposite end of said casing is a nipple 18, by means of which the sprinkler may be attached to a water supply pipe or hose 19 15 (see Fig. 1).

Within the tubular casing 13 is located a piston head 20 which divides the casing longitudinally into a pressure chamber 21 and a resistance chamber 22. The piston head 20 is of the double facing type, having oppositely disposed packing members 20^a, 20^b which are held in proper spaced relation and in position against collapse by means of disks 20^c. A bolt 20^d passing through the 25 several parts of said piston head secures them in proper relative positions.

Located within the pressure chamber 21 is a horizontally disposed piston stem or rack bar 23 which has an upturned end 24 30 attached to the piston head 20 by means of the bolt 20^d before referred to. The opposite end of said rack bar also has an upturned end 25 to which is fixed on its inner face, a block of rubber or like material 25^a, 35 the purpose of which will presently appear. The said rack bar is preferably made from stamped metal and has a longitudinally extending slot 26 along its approximate median line, defined by side members or bars 40 27 and 28 respectively. In that wall of the side member 27 partly defining said slot, is formed rack teeth 29. The other side member 28 is displaced upwardly so as to be located in a plane above that of the side 45 member 27.

An upright tubular sprinkler nozzle 30 (see Fig. 6), projects intermediate its ends through a bearing opening 11^a formed in the top of the tubular casing 11. Said nozzle is closed at its bottom end within the 50 pressure chamber 21 by means of a plug 31. In the bottom of said plug is formed a bearing recess 32 adapted to receive the reduced end 33 of an upright bearing screw 34 threaded through the saddle 14 of the base and through the bottom wall of the casing 11 respectively. Besides providing a rotative supporting bearing for the nozzle 30, said screw 34 assists in securing said tubular casing 11 to the base 12.

The bottom end of the plug 31 is made in the form of a gear wheel 36 which is adapted to mesh with the teeth 29 on the bar 27, while the raised side member 28 of said bar 60 engages the top side of said teeth and in

guiding relation against the upright tubular body of the nozzle 30. Thus endwise movement of the nozzle is prevented.

In that part of said nozzle within the chamber 21 is provided an opening 37 which 70 forms the water inlet from said chamber to the interior of the nozzle. The top end of said nozzle is closed by a rounded wall 38 in which are located water discharge openings 39 and 40 respectively. As shown, the opening 39 has straight sides while the opening 40 has tapered sides. As the water issues forth from these openings in streams, they will commingle and together form a curtain of water which will fall in a generous but 80 continuous spray upon the ground immediately adjacent the sprinkler and in a straight line to the farthest limit or throw provided by the pressure supplied through the hose 19. To prevent leakage of water 85 from the chamber 21 through the bearing opening 11^a about the sprinkler nozzle 30, and a consequent reduction of pressure in this chamber, I provide a gasket 41 about said opening on the outside of the tubular 90 casing 11. This gasket is seated in a recess 13^a formed in the top of the yoke 13.

The chamber 22 is adapted to contain a fluid, such as water, which resists the movement of the piston under the action of the 95 pressure in the chamber 21, but as the fluid in the chamber 22 is permitted to escape therefrom through a suitable valve mechanism, in the cap 16, it is apparent that the rate of movement of the piston and consequently the length of time to complete one movement thereof may be controlled to suit the will of the operator. This is brought about as follows: The cap 16 has an interiorly screw threaded tubular extension 16^a 100 adapted to receive a threaded valve stem 50. This valve stem is provided at one end without the casing 11 with a turning knob 51 by means of which it may be manipulated. The opposite end of said valve stem within the 105 chamber 22 is upset to form a valve head 52 which is adapted to close against a seat 53 formed by the adjacent parts of the gasket 17. The valve stem 50 is flattened on one side, as at 54, adjacent the head end 52, said 110 flattened part providing a passage way 55 (see Fig. 7) which provides communication between the interior of the chamber 22 and the atmosphere, when the valve head 52 is a short distance away from its seat 53. 115

The operation of my improved lawn sprinkler is as follows: With the parts in the position shown in Fig. 2, the cap 16 is removed from the casing and a quantity of water introduced into the chamber 22, after 120 which the cap 16 is replaced. The lawn sprinkler is placed upon the ground suitably connected to the hose 19. As is apparent from an inspection of Fig. 2 of the drawings, the inlet port 37 and discharge ports 125 130

39 and 40 of the nozzle, face toward the right or inlet end of the chamber 21 and as the water from the hose 19 enters said chamber 21, it will find its way into the interior 5 of the nozzle 30 through the said port 37. Inasmuch as the combined area of the nozzle discharge ports 39 and 40 is much less than that of the inlet opening in the nipple 18, a substantial pressure will build up in the 10 chamber 21 and be exerted upon the associated face of the piston 20. This pressure will cause the piston 20 and with it, of course, the stem or rack bar 23, to travel toward the left or cap end 16 of the casing, 15 this movement being resisted by the fluid in chamber 22.

As the nozzle 30 is operatively connected to the rack bar 30, as before described, a rotative movement will be imparted to said 20 nozzle. This movement of the piston may be resisted or increased by further closing or opening of the valve 50 in the cap to diminish or increase the escape of the resistance water from the chamber 22, as the 25 piston is moving. Thus the speed of rotation of the nozzle can be regulated.

As the piston approaches the cap 16, the upright end 25 will approach the nozzle 30. At the same time, the inlet port 37 of the 30 nozzle will approach an angular plane in its rotation, whereby the sealing block 25^a on the upright end 25 of the rack bar 23 will register therewith and close off said inlet opening 37 thus also shutting off water supply to the discharged openings 39 and 40. The water is then shut off from the hose 19 and the sprinkler bodily removed to another location, where the operation may be repeated, the piston 20 having first been moved 40 back to the position illustrated on Fig. 2, and the chamber 22 again filled with water as before described.

In Fig. 8 is illustrated a modified form of 45 sprinkler nozzle, the same consisting of a cap 60 adapted for suitable screw threaded engagement with the top end of the sprinkler nozzle 30. This cap has discharge or spraying ports 39^a, 40^a so located therein as to register with the discharge ports 39 and 50 40 of the nozzle 30. By rotating the cap 16 upon the nozzle 30 so that said ports register, the maximum discharge of water is had, but it will be manifest that by a further rotation of the said cap, this registration is 55 broken and the outlet for the water restricted. In other words, the cap 60 may be used to regulate the volume of water discharged from the nozzle.

When the cap 60 is made use of, the discharge ports 39 and 40 are preferably made 60 with parallel walls and the port 39^a of said cap also has parallel walls but the walls of the port 40^a are tapered as is the port 40 in the preferred form of construction.

65 I have found by actual use of this device,

that in cases where city ordinances prevent the use of a lawn sprinkler only between certain hours, say for example, from five to seven o'clock in the afternoon,—my improved sprinkler can be set into operation at 70 5 o'clock and by proper adjustment of the valve head 52, the passage of resistance water through the channel 55 will require two hours of time, thus giving the sprinkler 75 two hours of time for one complete rotation of the nozzle.

The sprinkler is very convenient for use in cities where it may be placed upon the edge of a lawn on the house side of the sidewalk and caused to rotate through only a 80 part of a complete rotation over a given area, thereby leaving the sidewalk clear and dry for pedestrians to pass while the sprinkler is in operation.

By constructing the valve in the cap 16 85 as described, the said cap may be removed from the casing 11 for the purpose of filling the chamber 22 with resistance fluid, without danger of said valve being accidentally displaced from the said cap and lost. The 90 sprinkler is simple in construction and, as is apparent, is cheap to manufacture, yet capable of efficient operation for its intended purpose.

While in describing my invention, I have 95 referred to certain details of mechanical construction and arrangement of parts, I do not wish to be limited thereto except as pointed out in the appended claims.

I claim as my invention:

1. A lawn sprinkler comprising a water pressure chamber, a spraying nozzle extending into said chamber and communicating with said chamber, a piston movable in said chamber, and means connecting said piston and nozzle and adapted to rotate the latter.

2. A lawn sprinkler comprising a water pressure chamber, a piston therein, a piston stem, means for regulating the rate of movement of the piston against the water pressure therein, a spraying nozzle in communication with the water chamber and operatively connected with the piston stem, to be rotated thereby.

3. A lawn sprinkler comprising a water 115 pressure chamber, a piston therein, a piston stem, means for regulating the rate of movement of the piston against the water pressure therein, a spraying nozzle in communication with the water chamber and 120 operatively connected with the piston stem to be rotated thereby and means for shutting off the supply of water to the nozzle.

4. In a sprinkler the combination of a water pressure chamber, a piston movable 125 therein, a piston stem, means for regulating the rate of movement of the piston against the water pressure therein, a rotatable spraying nozzle in communication with the water chamber, means connecting the piston stem 130

and nozzle and adapted to rotate the latter, and mechanism for automatically shutting off the supply of water to the nozzle.

5. In a sprinkler the combination of a water pressure chamber, a piston movable therein, a piston stem, provided with a rack bar, a spraying nozzle in communication with the water chamber, a pinion connected with said nozzle and having its teeth in mesh with said rack bar, and means for regulating the rate of movement of the piston.

6. An automatic sprinkler comprising a water pressure chamber, a piston movable therein, a piston stem, means for regulating the rate of movement of said piston, a spraying nozzle having an inlet port in communication with said chamber, means connected with the piston stem for rotating the nozzle, and means carried by said piston stem for closing off said nozzle inlet port when said piston is at the limit of its movement in said pressure chamber.

7. An automatic sprinkler comprising a water pressure chamber, a piston movable therein, means for regulating the rate of movement of said piston, a piston stem, a spraying nozzle having an inlet port in communication with said chamber, means connecting the piston stem and nozzle and adapted to rotate the latter, and a sealing block carried by said piston stem adapted to close said nozzle inlet port when said piston is at the limit of its movement in said pressure chamber.

35 8. A sprinkler device comprising a water pressure chamber, a piston movable in said chamber, a piston stem, a spraying nozzle in communication with said chamber and rotatively connected with the piston stem, means for shutting off the supply of water to the nozzle, the said spraying nozzle having exit or spraying ports at its exposed end, and a cap for regulating the amount of water to flow through said exit or spraying ports.

9. A sprinkler comprising a pressure chamber, and a resistance chamber, a movable piston separating said chambers, a rotatable spraying nozzle having an inlet port in communication with said pressure chamber, and discharge ports without said chamber, coöperating means whereby the nozzle

is rotated by the reciprocation of the piston, and means for decreasing the resistance in said resistance chamber whereby the rate of 55 movement of the piston may be regulated.

10. A sprinkler device comprising a casing providing a water pressure chamber and a resistance chamber adapted to contain a resistance fluid, a piston movable in 60 said casing and separating said chambers, a piston stem, a rotatable spraying nozzle extending into and communicating with the water pressure chamber and operated by the movement of the piston stem, and a valve 65 device controlling the escape of resistance fluid from said resistance chamber to vary the resistance therein against said piston.

11. A sprinkler device comprising a tubular casing providing a water pressure chamber and a resistance fluid chamber, a piston movable in said casing and separating said chambers, a piston stem, a rotatable spraying nozzle extending into and communicating with the water pressure chamber and 70 operated by the movement of the piston stem, a cap forming one end of said resistance fluid chamber and a valve in said cap adapted to control the escape of fluid from said resistance chamber to vary the resist- 75 ance against said piston.

12. A sprinkler device comprising a tubular casing providing a water pressure chamber and a resistance fluid chamber, a piston movable therein, a piston stem, a rotatable 80 spraying nozzle extending into and communicating with the water chamber and operated by the movement of the piston stem against the resistance of the fluid in said resistance chamber, said nozzle having a discharge end without the casing, a base for said casing and a yoke clamping said casing to said base, said yoke surrounding said nozzle without the casing and having means providing a pressure tight joint between said 85 casing and spraying nozzle.

In testimony that I claim the foregoing as my invention I affix my signature in the presence of two witnesses, this 13th day of October, A. D. 1916.

FINIS EWING ROACH.
